(57) **CLAIM**

The ornamental design for an audio visual alarm housing, as shown and described.

DESCRIPTION

FIG. 1 is a perspective view of an audio visual alarm housing showing our new design; and,

FIG. 2 is a left elevational view thereof.

Views of the audio visual alarm housing not shown, including a back view, are disclaimed and are not part of the claimed design.

1 Claim, 2 Drawing Sheets

FIG. 1

FIG. 2
